KEY RACK

Harold Hoffman, 6247 N. Western Ave., Chicago, Ill.

Filed Mar. 20, 1958, Ser. No. 722,740

5 Claims. (Cl. 211—59)

This invention relates to devices for holding keys or key blanks, and has more particular reference to key racks of the type commonly used to hold a large assortment of key blanks at stations where the blanks are cut or notched to order.

In the past, most key racks of this nature comprised a stiff panel, usually of sheet metal, having key holding members formed of wire mounted in rows thereon. Each such member was provided with a prong extending forwardly from one face of the panel to support several identical key blanks.

One of the problems presented by this type of key rack was the difficulty of providing for firm anchoring of the key supporting members against all motion with respect to the rack without resorting to tedious and costly manufacturing and assembly operations including the riveting of each key holding member to the rack panel.

In general, it is the purpose of this invention to provide an improved key rack construction by which the aforesaid objections are overcome. In this respect it is a purpose of this invention to provide an improved key rack featuring firm anchoring of the key holding members against all motion with respect to the rack without the need for riveting them in place, and wherein an easily assembled retaining means common to all of the key holding members is employed to secure them in place on the panel.

Another purpose of this invention is to provide a key rack of the character described having improved key holding members per se, so formed that each member comprises a pair of spaced key supporting prongs and a bridge piece connecting the prongs and with which the common retaining means for the members is engageable to firmly clamp the members against all motion relative to the rack.

Still another object of this invention resides in the provision of a key rack of the character described which is comprised of juxtaposed front and rear panels, and wherein the prongs of the key supporting members project forwardly through holes in the front panel while the bridge pieces which connect adjacent prongs are clampingly confined between the panels with the major portion of each bridge piece receding from and offset with respect to the plane of the prongs.

With the above and other objects in view which will appear as the description proceeds, this invention resides in the novel construction, combination and arrangement of parts substantially as hereinafter described and more particularly defined by the appended claims, it being understood that such changes in the precise embodiment of the herein disclosed invention may be made as come within the scope of the claims.

The accompanying drawing illustrates several complete examples of the physical embodiments of the invention constructed according to the best modes so far devised for the practical application of the principles thereof, and in which:

Figure 1 is a perspective view of a key rack embodying

2

the principles of this invention, parts thereof being broken away and shown in section;

Figure 2 is a cross sectional view taken through the rack of Figure 1 along the plane of the line 2—2;

5 Figure 3 is a perspective view of a modified form of key holding member per se; and

Figure 4 is a perspective view of still another form of key holding member per se.

Referring now particularly to the accompanying drawing wherein like reference characters have been applied to like parts throughout the views, the key rack of this invention comprises an upright, substantially flat rectangular base 5. The base is comprised of substantially flat front and rear sheet metal panels 6 and 7, respectively, of rectangular shape and of substantially the same size.

The front and rear panels are connected together by means which holds them in flatwise juxtaposition, with their corresponding side and end margins substantially coincident. While this may be effected in many ways, it 15 is a feature of this invention that this connection is established by means which includes elongated flanges 8 on each of the side margins of the front panel, bent around to the rear thereof and engaged over the marginal side edge portions 9 of the rear panel 7. The side edge portions 9 of the rear panel are offset a slight distance forwardly of the body portion of the panel and flatwise engage the back of the front panel to establish a slight space between the body portions of the juxtaposed panels. The marginal edge portions 9 of the rear panel are 20 slidably received in the channel-like guides provided by the flanged side edges of the front panel and constrained thereby to endwise sliding motion to and from its assembled position on the rack at which it cooperates with the front panel to provide the base 5.

25 In addition to the side flanges 8, the front panel 6 is also provided with an end flange 10 at its top which is bent around and engaged over the upper marginal edge portion of the rear panel 7 to define the assembled positions of the panels. The end flange 10 thus cooperates 30 with the side flanges 8 to constrain the rear panel to endwise detachment and/or assembly from one end of the front panel, namely that end thereof which is remote from the end flange 10.

The front panel is provided with a number of spaced 35 horizontal rows of holes 11 therein with the holes of the rows arranged in equi-spaced pairs of holes which are spaced a uniform distance from each other. As shown, therefore, each row consists of four pairs of holes or a total of eight holes, and all of the holes in the various 40 rows are of the same size. Preferably the holes 11 in the several rows thereof are also arranged in vertical rows, as seen best in Figure 1 of the drawing.

An elongated substantially straight key supporting prong 12 projects forwardly through each of the holes 11 and each of the prongs may have its outer end portion turned up, as indicated at 13. The prongs 12 which project through each pair of adjacent holes 11 are formed as an integral part of a key holding member, generally designated 14, formed of substantially stiff wire of a diameter 55 to fit the holes 11. Each of the key holding members has a bridge piece 15 which occupies a plane substantially normal to the prongs thereof and is clampingly confined between the front and rear panels 6 and 7 to 60 serve as an anchor by which the prongs of the member are held against all motion relative to the base.

65 Each of the key holding members 14 shown in Figure 1 has a bridge piece 15 which is of inverted U-shaped configuration to provide a bight portion 16 substantially parallel to a line joining the proximal ends of the prongs 12, and to provide opposite legs 17 which project downwardly from the ends of the bight portion 16 and have

their outer ends integrally joined to the inner ends of the prongs 12.

The described manner of mounting the key holding members on the base provides for exceptional stability of the prongs 12 primarily because of the fact that pairs of adjacent prongs are joined by bridge pieces 15 which have major portions thereof offset a substantial distance from a plane containing the prongs. Also, it will be seen that because each of the prongs 12 is connected to an adjacent prong, the prongs themselves prevent rotation thereof on their axes; while the more or less flatwise confinement of the bridge pieces 15 against the rear of the front panel prevents all other motion of the prongs with respect to the panels.

While the body portion of the rear panel 7 may be substantially flat, it is preferably formed with a series of forwardly displaced vertical corrugations 19, alternate ones of which cross over and bear upon the bight portions 16 of the bridge pieces of all the key holding members to thus assure that the bridge pieces will be securely clamped against the rear face of the front panel 6. The corrugations, of course, also serve to stiffen the base 5.

It should be noted that the opposite legs 17 of all of the bridge pieces 15 extend from the inner ends of the prongs 12 toward the flange 10 at the upper end of the base. This feature is highly important since it facilitates securing of all of the key holding members 14 to the base upon assembly of the rear panel 7 to the back of the front panel 6. Such assembly is preferably accomplished with the rack in an inverted position and held with the U-shaped bridge pieces 15 all hanging downwardly along the rear of the front panel, toward the flange 10. With the parts held in this manner, the rear panel 7 may be inserted into the channel-like guides on the opposite sides of the front panel and slid endwise downwardly into place on the rear panel until it abuts the end flange 10. As it is thus slid into place, the rear panel rides over each successive row of bridge pieces 15, which in their depending positions, offer no obstacle to such assembly of the rear panel.

After the two panels have been brought into flatwise juxtaposition, the rear panel is held against endwise detaching motion by sheet metal screws 21 engaged in suitable aligning holes in the panels. Two such sheet metal screws 21 located on the vertical centerline of the base, one near the top and one near the bottom thereof, are sufficient to prevent displacement of the rear panel from its operative position seen in Figure 1. The disposition of the screws 21 also assures that the medial portion of the retaining panel 7 will not bow rearwardly out of clamping engagement with respect to the bridge pieces of the key holding members.

The base is also provided with a series of four holes 24, one in each corner area of the base. These holes extend through both the front and rear panels and provide for mounting the rack on an upright supporting surface as by means of screws (not shown).

If desired, the key holding members may be provided with bridge pieces 25 which are bent to substantially serpentine shape, as shown in Figure 3. In the construction therein illustrated the key holding members are likewise made of a single length of relatively stiff wire having spaced substantially parallel opposite prongs 12 joined at their proximal ends to the lower ends of the vertical legs 26 on the bridge pieces 25. The legs 26, of course, correspond to the legs 17 of the inverted U-shaped bridge pieces described previously, but in this case the bight portion of the bridge piece is substantially V-shaped and the extremities of its diverging branches 27 are joined to the upper ends of the legs 26. The apex portion 28 of the V-shaped bight, however, is disposed beneath the line which joins the inner ends of the prongs 12 and is spaced a distance therefrom substantially equal to the height of the legs 26, so that both branches 27 of the bight cross said line.

The bridge piece 25, of course, occupies a plane which is substantially normal to the plane containing the prongs 12, and it provides the desired degree of stability for the prongs when confined between the front and rear panels by reason of the fact that its major portion recedes from a plane containing the prongs. The key holding member of Figure 3, in fact, has portions disposed substantially equal distances to opposite sides of the plane containing the prongs 12 so as to assure against all motion of the prongs with respect to the panels between which the bridge piece may be clamped.

The key holding member seen in Figure 4 has a bridge piece 30 integrally joining the inner ends of the prongs 12 but so shaped that its legs 31 extend equal distances 15 in opposite directions from the plane of the prongs. In other words, one of the legs extends upwardly and the other downwardly, and their outer ends are joined by a diagonal bight portion 32. The bridge piece 30 is thus 20 also of serpentine shape having major portions thereof which recede from the plane of the prongs 12 and having a single portion 32 crossing the plane of the prongs.

From the foregoing description taken with the accompanying drawings, it will be readily apparent to those skilled in the art that this invention provides an improved key rack which features unusual stability for the key supporting prongs along with ease of manufacture and assembly of the components of the rack.

What is claimed as my invention is:

- 30 1. A key rack of the character described comprising: front and rear panels; means connecting said panels and holding them in flatwise juxtaposition; the front panel having a number of spaced apart parallel rows of holes therein with the holes of said rows arranged in equi-spaced pairs of holes which are spaced a uniform distance from one another, the holes of said parallel rows thereof also lying in straight rows which are normal to said parallel rows; and key holding members, each having a pair of key supporting prongs which project forwardly through the holes of each said pair thereof, and a bridge piece confined between said panels, said bridge piece having legs joined at one end to the inner ends of the prongs of said member and extending therefrom substantially lengthwise of said straight rows, and a part extending between and joining the opposite ends of said legs; and reinforcing corrugations in said rear panel indented forwardly therefrom toward the front panel and arranged in rows parallel to said straight rows of holes but intermediate said pairs of holes in the parallel rows, the corrugations engaging said parts of the bridge pieces 50 of all of the key holding members and holding said bridge pieces clamped against the back of the front panel to thereby anchor the prongs of the members against all motion with respect to the panels.

- 55 2. The key rack of claim 1 further characterized by the fact that: each of said bridge pieces is substantially U-shaped and has its legs extending in the same direction from the prongs to which they are joined, substantially parallel to said straight rows of holes, and the bights of the U-shaped bridge pieces being disposed substantially normal to said straight rows of holes and constituting said parts which are clampingly engaged by the corrugations in the rear panel.

- 60 3. In a key rack of the character described: a substantially flat rectangular base comprised of flatwise juxtaposed front and rear panels having opposite substantially coincident vertically extending side margins and opposite substantially coincident horizontally extending end margins; the front panel having a number of spaced horizontal rows of holes therein with the holes in each row arranged in pairs, the holes of said horizontal rows also lying in vertical rows; key holding members each 70 comprised of a pair of key supporting prongs which project forwardly through the holes of each said pair thereof and which are substantially perpendicularly joined to

the outer ends of the opposite legs of a U-shaped bridge piece closely confined between the panels to serve as an anchor by which the prongs are held against all motion relative to the base, the bight portion of said U-shaped bridge piece extending transversely between and joining the inner ends of said legs, remote from the prongs of the member, and the legs of all of the key holding members extending in the same direction toward one of said horizontal end margins of the base; means on the base constraining the rear panel to endwise vertical detaching motion in the opposite direction; and means on the base releasably holding the rear panel against such endwise detaching motion.

4. The key rack of claim 3 further characterized by: the fact that said constraining means comprises flanges on the opposite sides of the front panel extending around the adjacent marginal side edge portions of the rear panel, and a similar flange on the end of the front panel toward which the legs of the bridge pieces extend and defining the assembled position of the rear panel, said flanges cooperating with said releasable means to hold the panels in flatwise juxtaposition with the U-shaped bridge pieces snugly confined therebetween.

5. A key rack of the character described comprising: front and rear panels; means connecting said panels and holding them in flatwise juxtaposition; the front panel having a number of spaced apart parallel rows of holes therein with the holes of said rows arranged in pairs, the holes of said parallel rows thereof also lying in

5
10

20
15

straight rows which are normal to said parallel rows; and key holding members, each having a pair of key supporting prongs which project forwardly through the holes of each said pair thereof, and a bridge piece confined between said panels, said bridge piece having legs joined at one end to the inner ends of the prongs of said member and extending therefrom substantially lengthwise of said straight rows, and a part extending between and joining the opposite ends of said legs; and reinforcing corrugations in one of said panels indented toward the other of said panels and arranged in spaced substantially parallel rows, said corrugations being spaced from each said hole and engaging the bridge pieces of all of the key holding members and holding the same clamped against the other of said panels to thereby anchor the prongs of the members against all motion with respect to the panels.
